(57) **CLAIM**

The ornamental design for a wire connector, as shown and described.

DESCRIPTION

FIG. 1 is a perspective view of a wire connector showing my new design;

FIG. 2 is a rear elevation view thereof;

FIG. 3 is a front elevational view thereof;

FIG. 4 is a top plan view thereof;

FIG. 5 is a bottom plan view thereof;

FIG. 6 is a right side elevational view thereof; and,

FIG. 7 is a left side elevational view thereof.

1 Claim, 7 Drawing Sheets(56)
